US0D1007320S

(12) **United States Design Patent** (10) **Patent No.:** **US D1,007,320 S**
(45) **Date of Patent:** **** Dec. 12, 2023**

(54) **DISPENSER**

(71) Applicant: **Method Products, PBC**, San Francisco, CA (US)

(72) Inventor: **Louis Filosa**, San Francisco, CA (US)

(73) Assignee: **Method Products, PBC**, San Francisco, CA (US)

(**) Term: **15 Years**

(21) Appl. No.: **29/750,274**

(22) Filed: **Sep. 11, 2020**

(51) LOC (14) Cl. **09-01**

(52) U.S. Cl.

USPC **D9/682; D9/542**

(58) **Field of Classification Search**

USPC D9/682-694, 529, 560, 575, 500, 501, D9/503, 504, 549, 558, 737-747, 652, D9/600, 530, 542, 543, 562, 572-574, D9/729, 730-732; D3/202, 270, D3/271.1-271.4, 203.2, 265; D24/197; D28/76, 77, 7

CPC B05B 11/0038; B05B 11/0054; B65D 2543/0092

See application file for complete search history.

(57) **CLAIM**

The ornamental design for a dispenser, as shown and described.

DESCRIPTION

FIG. 1 is a top perspective view of a dispenser showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the dispenser that form no part of the claimed design.

1 Claim, 7 Drawing Sheets
